CLAIM

The ornamental design for an illuminated reel cover for a slot machine, as shown and described.

DESCRIPTION

FIG. 1 is a front elevational view of the illuminated reel cover for a slot machine;

FIG. 2 is a right elevational view of the illuminated reel cover for a slot machine;

FIG. 3 is a perspective view of the illuminated reel cover for a slot machine;

FIG. 4 is a left elevational view of the illuminated reel cover for a slot machine;

FIG. 5 is a top plan view of the illuminated reel cover for a slot machine; and,

FIG. 6 is a bottom view of the illuminated reel cover for a slot machine.

The dotted line showing of the slot machine and indicia are for illustrative purposes only, and forms no part of the claimed design.
